DEMOUNTABLE DRAIN STRAINER

Filed April 8, 1931

INVENTOR
Maurice Alland,
BY
J. Stuart Freeman,
ATTORNEY

UNITED STATES PATENT OFFICE

MAURICE ALLAND, OF ATLANTIC CITY, NEW JERSEY

DEMOUNTABLE DRAIN STRAINER

Application filed April 8, 1931. Serial No. 528,488.

The object of the invention is to provide improvements in strainers for drains, particularly those found in bathtubs, sinks, basins, and the like, wherein it is frequently desired to thoroughly clean the same without having to employ wrenches, screw-drivers, or other forms of tools.

Another object is to provide an improved strainer which can be inserted into and removed from the outlet of a wide variety of basins or the like, without in any way altering the latter or the pipe connections associated with the same.

A further object is to provide a strainer which extends through or adjacent to the upper exposed surface of the water in the basin, whereby the valve-releasing means is accessible without necessitating immersing one's hand in the water, as when its temperature is unpleasantly high for comfort, or when it contains substances which it is desired that the hand shall not come into contact with.

Still another object is to provide in such a device the combination of a casing adapted to readily fit within drain fittings of widely different diameters, said casing being provided with an outlet orifice in alignment with the drain pipe and with one or more inlet openings above the normal level at which the casing cooperates with the fitting, a removable strainer element being normally positioned within said casing and covering said inlet openings, a closure normally spanning the upper free end portion of said casing, and a rod in threaded engagement with and extending through said closure and carrying a valve upon its inner end adapted to cooperate with and close at will said outlet orifice, and said closure being removable for the purpose of removing and cleaning both the valve and the strainer.

And a still further object is to provide such a strainer device with means, adapted to loosely engage the inner walls of the usual drain

pipe to prevent the device from unduly tilting, and also adapted to engage the usual spider within the drain fixture to prevent the said device from rotating whenever the valve-actuating rod is rotated.

With these and other objects in mind, the present invention comprises further details of construction and operation which are fully brought out in the following description when read in conjunction with the accompanying drawings, in which Fig. 1 is a vertical section through the lower portion of a representative type of sink or basin, and showing the improved strainer in operative position and in elevation; Fig. 2 is a bottom plan view of the strainer per se; Fig. 3 is a vertical diametrical section of the same; and Fig. 4 is a section on the line 4—4 of Fig. 1.

Referring to the drawings, the lower portion 1 of a representative type of sink or basin is shown as being provided with a drain outlet 2, in association with which is any well-known type of tubular fixture 3, which is spanned upon its interior by a spider or set of angularly disposed ribs 4, the function of which is always to prevent large particles entering said fixture and passing through the same and into the drain pipe 5 extending therefrom. The fixture 3 is surrounded by a cylindrical member 6, which forms a virtual extension of said fixture and is provided with a radial flange 7 to protect the adjacent edge portion of the basin surrounding the outlet aperture 2.

The preferred embodiment of the invention comprises an inverted conical casing 8, partially closed at its normal lower end by a wall 9 having a central outlet orifice 10, said orifice being surrounded by a plurality of spaced parallel bars 11 supported by said wall and normally extending into and at least partially through the fixture 3, so as to loosely engage the inner surface of the walls of said fixture, as suggested by Fig. 1, and thus prevent said casing from tilting into such an

inoperative angle that the substantially liquid-tight cooperation between the casing and drain fixture would be destroyed and permit liquid to pass by and between the same.

5 The walls of said casing extend upwardly in the form of angularly disposed ribs 12 which space apart a plurality of inlet apertures 13, which in turn are normally spanned by means of an inverted conical strainer element 14, which is removably positioned within said casing, as clearly shown in Fig. 3.

The normal upper portion of said casing is spanned by a closure 15 in threaded engagement at 16 with said casing, and provided 15 with a central bushing 17, through which rotatably extends in threaded engagement a rod 18, carrying upon its upper free end a manually engageable knob or head 19, and its inner and normal lower end comprising 20 a valve 20, adapted to close the outlet orifice 10 of said casing. With the device in its normal operative position, as shown in Fig. 1, and with the valve closing the casing outlet 10, as shown in Fig. 3, liquid may be 25 placed within the basin 1 at the desired height and it will not flow therefrom, until the knob 19 of the valve rod 18 is rotated in such manner as to withdraw said valve from said outlet orifice. Said knob may extend above the surface of the liquid within the basin if desired, and in any case its relative rotation with respect to said casing is assured within predetermined limits by virtue of the fact that said casing cannot rotate 35 very far due to the engagement of said bars 11 with the ribs of the spider 4. Thus, when it is desired that the liquid within said basin is to be discharged therefrom, said valve is actuated to permit the liquid to flow through 40 the inlet openings 13 of said casing, through the strainer element 14 and thence through the casing outlet orifice 10.

When, as in the case of so-called beauty parlors and elsewhere, an accumulation of 45 hair and other undesirable foreign matter has gathered about the device in general and against the outer surface of the strainer element 14 in particular, the device may at any time be lifted bodily from engagement with the fixture 3 and associated elements, the closure 15 removed from said casing, and the strainer element then freely withdrawn so as to permit all of the several parts of the device to be easily and thoroughly cleansed 50 in any desired manner, after which they may be reassembled as here illustrated, either at once or when their further use as a unit is desired.

Having thus described my invention, what 60 I claim and desire to protect by Letters Patent of the United States is:—

65 1. A drain strainer, comprising a casing adapted to be inserted into and to extend freely from a drain fixture connected with a drain pipe, said casing having an outlet in align-

ment with the fixture and also an inlet, a removable closure for said casing, a valve for said outlet, a valve-actuating rod extending through said closure, and a strainer element within said casing and covering said inlet, and removable therefrom after the removal of said closure. 70

2. A drain strainer, comprising a casing adapted to be inserted into and to extend freely from a drain fixture connected with a drain pipe, said casing having an outlet in alignment with the fixture and also an inlet, a removable closure for said casing, a valve for said outlet, a valve-actuating rod extending through said closure, and means carried by and extending from said casing normally into and in engagement with the walls of the drain pipe to prevent said casing from tilting into a position out of substantially liquid-tight cooperation with the fixture, and cooperating with the fixture to prevent rotation of said casing when said rod is rotated. 75 80

3. A drain strainer, comprising a casing adapted to be inserted into and to extend freely from a drain fixture connected with a drain pipe, said casing having an outlet in alignment with the fixture and also an inlet, a removable closure for said casing, a valve for said outlet, a valve-actuating rod extending through said closure, a strainer element within said casing and covering said inlet, and removable therefrom after the removal of said closure, and means carried by and extending from said casing normally into and in engagement with the walls of the drain pipe to prevent said casing from tilting into a position out of substantially liquid-tight cooperation with the fixture, and cooperating with the fixture to prevent rotation of said casing when said rod is rotated. 90 95

4. A drain strainer, comprising an inverted conical casing having an imperforate portion adapted to be inserted into and engage the sides of drain fixtures of widely varying diameters, said casing having an outlet in alignment with the fixture and an inlet above its highest point of permissible engagement with a drain fixture, a removable closure for said casing, a valve for said outlet, a valve-actuating rod extending through said closure, and a strainer element covering said inlet within said casing, and removable therefrom after removal of said closure. 100 105 110

5. A drain strainer, comprising an inverted conical casing having an imperforate portion adapted to be inserted into and engage the sides of drain fixtures of widely varying diameters, said casing having an outlet in alignment with the fixture and an inlet above its highest point of permissible engagement with a drain fixture, a removable closure for said casing, a valve for said outlet, a valve-actuating rod extending through said closure, a strainer element covering said inlet within said casing, and removable therefrom after 115 120 125 130

removal of said closure, and means carried by
and extending from said casing normally into
and in engagement with the walls of the drain
pipe to prevent said casing from tilting into
5 a position out of substantially liquid-tight
cooperation with the fixture, and cooperating
with the fixture to prevent rotation of said
casing when said rod is rotated.

In testimony whereof I have affixed my
10 signature.

MAURICE ALLAND.
